UNITED STATES PATENT OFFICE

95,460

DESIGN FOR A GLASS BOTTLE

Earl A. Sheffield, Muncie, Ind., assignor to Ball Brothers Company, Muncie, Ind., a corporation of Indiana

Application February 14, 1935, Serial No. 55,431

Term of patent 14 years

To all whom it may concern:

Be it known that I, Earl A. Sheffield, a citizen of the United States, residing at Muncie, in the county of Delaware and State of Indiana, have invented a new, original, and ornamental Design for a Glass Bottle, of which the following is a specification, reference being had to the accompanying drawing, forming part thereof.

In the drawing:—

Fig. 1 is a front elevation of a bottle embodying
the new design;

Fig. 2 is a side elevation, and
Fig. 3 is a bottom plan view.

I claim:—

The ornamental design for a glass bottle, as shown.

In testimony that I claim the foregoing as my own, I have hereunto affixed my signature.

E. A. SHEFFIELD.
